UNITED STATES PATENT OFFICE.

ROLAND E. JOHNSON, OF MEDFORD, MASSACHUSETTS.

WINDOW-LOCK.

1,392,335.

Specification of Letters Patent. Patented Oct. 4, 1921.

Application filed December 18, 1918. Serial No. 267,274.

To all whom it may concern:

Be it known that I, ROLAND E. JOHNSON, a citizen of the United States, residing at Medford, in the county of Middlesex, State 5 of Massachusetts, have invented a new and useful Window-Lock; and I do hereby declare the following to be a full, clear, and exact description of the invention, such as will enable others skilled in the art to which 10 it appertains to make and use the same.

This invention relates to an improved sash lock or latch, and one of the objects of the invention is to provide a device of this kind, which is simple in construction, effective in operation, and may be manufactured 15 for a small cost and sold at a reasonable profit.

A further object of the invention is to provide a latch having a spring tension latch hook supported on the upper rail of the lower sash, and adapted to engage a stationary hook on the lower rail of the upper sash, when the lower sash is lowered.

A further object of the invention is the 25 provision of means carried upon the lower rail of the upper sash to support the spring tension latch hook free of the hook of the lower rail of the upper sash, whereby either one of the sashes may be opened. However, 30 when either one or both of the sashes are closed the spring tension latch hook will automatically engage the stationary hook, thereby holding both sashes locked when closed.

35 In practical fields, the details of construction may necessitate alterations falling within the scope of what is claimed.

The invention comprises further features and combination of parts, as hereinafter set 40 forth, shown in the drawings, and claimed.

In the drawings:

Figure 1 is a perspective view of the meeting rails of the upper and lower sashes, showing the improved sash latch and slide.

45 Fig. 2 is a vertical sectional view on line 2-2 of Fig. 1, showing in dotted lines the spring tensioned latch hook as supported out of engagement with the stationary hook.

Fig. 3 is a detailed view of the spring tensioned latch hook and a portion of its support, showing the arrangement of the spring.

Referring more especially to the drawings, 1 designates the upper rail of a lower 50 window sash, and on the upper face of 55 which, by means of screws 2, a bracket 3

is secured. This bracket comprises a base 4, and is U-shaped as shown. Mounted in the upper ends of the spaced upstanding arms or sides 5 is a pin or shaft 6. A latch hook 7 is pivotally mounted upon the pin or shaft, there being a spring 8 carried by the pin or shaft and engaging the latch hook for retaining the same in operative position. The lower end of the latch has a hook portion 9, and projecting laterally from the latch is an arm 10. Secured by screws 11 to the upper face of the lower rail of the upper sash is a plate 12, and rising upwardly from the plate is a stationary hook 13, with which the hook 9 of the latch 7 engages, when the lower sash is lowered, or when the upper sash is raised to a closed position. Also rising upwardly from the plate 12 is a flexible lug 14. When it is desired to raise or open 70 the lower sash or lower or open the upper sash, the lateral arm 10 is grasped, and the latch 7 lifted, sufficiently to permit the arm 10 to engage over the flexible lug 14 and rest in engagement therewith. Obviously the 75 upper sash may then be lowered or the lower sash raised. However, when either one or both of the sashes are closed, the hook 9 of the latch 7 will automatically engage the stationary hook 13, thereby locking the two 80 sashes. When the lateral arm 10 is in engagement with the flexible lug 14, the shoulder 15 of said arm 10 will prevent the lateral displacement of the latch, incident to a pressure that may be applied to one edge 85 of the latch. The flexible lug 14 being in engagement with the side of the latch 7 at a point opposite to the side engaged by the shoulder 15, it will be seen that lateral movement of the latch 7 in the opposite direction 90 to that set forth above will be prevented when an instrument is forced upwardly between the rails of the sashes. It is obvious 95 that since the flexible lug is in the path of the arm 10 when the latch 7 is forced upwardly that the hook 9 of the latch 7 will when it is forced upwardly come into engagement with the enlarged portions 16 of the flexible lug thereby preventing the raising 100 of the latch 7 to a point where it would not fall by gravity into engagement with the stationary hook 13. The flexible lug is so positioned that it will prevent the raising 105 of the latch 7 by the instrument when it is forced between the rails of the sash to a point where it would have sufficient leverage 110 to flex the flexible lug.

The invention having been set forth, what is claimed as new and useful is:—

In a window sash latch the combination with a stationary hook on the lower rail of the upper sash, of a spring tensioned latch hook pivotally supported on the upper rail of the lower sash, said spring tensioned latch hook being inclined downwardly and overlying the lower rail of the upper sash at an acute angle for engagement with said stationary hook when the two sashes are closed, said latch hook having a lateral arm, and a flexible lug carried by the lower rail of the upper sash and adapted to be engaged by said lateral arm to support the latch and

hold its hook out of engagement with the stationary hook, said lug extending into the path of movement of said arm and adapted to be flexed back thereby on opening or closing the window, and to spring back into said path to hold the latch out of operative position. 20

In testimony whereof I have signed my name to this specification in the presence of two subscribing witnesses.

ROLAND E. JOHNSON.
